UNITED STATES PATENT OFFICE.

FRED W. COOLEY, OF MINNEAPOLIS, MINNESOTA.

TONE MODIFIER FOR PHONOGRAHS.

1,423,832.

Specification of Letters Patent. Patented July 25, 1922.

Application filed April 4, 1921. Serial No. 458,432.

To all whom it may concern:

Be it known that I, FRED W. COOLEY, a citizen of the United States, residing at Minneapolis, in the county of Hennepin and State of Minnesota, have invented certain new and useful Improvements in Tone Modifiers for Phonographs; and I do hereby declare the following to be a full, clear and exact description of the invention, such as will enable others skilled in the art to which it appertains to make and use the same.

This invention relates to sound reproducing machines generally designated as talking machines or phonographs and the invention is particularly directed to the sound chamber or tone arm or tubes of such machines.

It is an object of the invention to construct the tone arms or sound chambers of talking machines so that an improved tone is produced thereby.

The invention disclosed in the present application is an improvement upon that disclosed and claimed in my prior Patent No. 1,349,604, granted August 17, 1920, and No. 1,352,115 granted September 7th, 1920. The purpose and object of the invention will be readily understood from the following description made in connection with the accompanying drawings in which like reference characters refer to the same parts throughout the several views, and in which—

Fig. 1 is a view showing the tone arms of a talking machine with the improvement applied thereto;

Fig. 2 is a section of the device of the invention taken substantially on the line 2—2 of Fig. 1 looking in the direction of the arrows;

Fig. 3 is a similar section with some of the parts removed; and

Fig. 4 is a section on an enlarged scale taken substantially on the line 4—4 of Fig. 1.

Referring to the drawings, the tone arm of a talking machine which is of ordinary shape, is designated as 1 and is provided at its base with a flange 1^a, by means of which it is attached to the top of the sound chamber and from said flange the sleeve 1^b depends in which is fitted the upper end of the tube 2, which tube is adapted to be disposed in the sound chamber of any standard type of talking machine and to form a part of the sound chamber or sound transmitting

conduit thereof. The tube 2 is tightly fitted into the sleeve 1^b and is supported thereby, and this tube, as shown in Fig. 1, may be cut away on an inclined plane at one end, as shown in Fig. 1, to expose a portion of the tube 3 supported therein. The tube 3 has its walls of less thickness than the walls of the tube 2 and said tube is also of less diameter than the tube 2, so that its sides are spaced from the under side thereof. The tube 2 is clamped at its lower portion to the tube 3, a pad member *a* being interposed between the tubes. Spaced headed and nutted bolts 4 extend through a clamping member 5 disposed on the outside of tube 2, and in which the heads of the bolts 4 are shown as being countersunk, and clamping plates 6 held in the inner ends thereof by suitable nuts. The pad *a* is formed of compressible and yielding material and comprises layers 7 of compressible fibrous material which is preferably leather impregnated with wax. The layers 7 are secured to the sides of the tubes by a suitable adhesive. A layer of softer fabric or fibrous material 8, preferably of a material such as soft wool, is disposed substantially at the center of the pad and sheets of unyielding or incompressible material 9, which material is preferably mica, are disposed at each side of the layer 8 and the layers 9 are then enclosed between folds of another piece of wax impregnated leather 10. Other sheets of mica 11 are placed at each side of the initial folds of the member 10 and are, themselves, enclosed in outside layers or folds of this member. The outside folds or layers of the members 10 are adjacent the layers 7, as clearly shown in Fig. 4.

A spring member 12 comprising a piece of steel wire, such as piano wire, is bent into the general form of a hair pin with its bight portion extending downwardly and is clamped between the plate 6 and a pad member *b*, which pad member contacts with the inner side of the tube 3. The spring 12 has its inner ends extending a considerable distance upwardly along the inner side of the tube 3 and its free ends are bent inwardly to contact with the inner surface of said tube, the spring being placed under tension by the upper bolts 4, so that such ends are held firmly in contact with the tube. At its lower portion, the spring 12 is surrounded

by a layer 13 of the wax impregnated leather. The pad *b* is similar in construction to the pad *a* disposed between the tubes 2 and 3 above described and comprises the 5 central layer of cloth and the alternate layers of mica and leather. It will be understood that the spring 12 and tube 3 are thus firmly clamped to the tube 2 by the bolts 4 passing through the interposed pad members. 10 As set forth in the prior patents, the nuts on the bolts 4 can be adjusted to aline the tube 3 concentrically with the tube 2 and, as already stated, the spring 12 is placed under tension by said clamping bolts 15 so that the upper end thereof bears firmly against the innerside of the tube 3. It will also be noted that the bolts 4 are surrounded at their outer portion and headed portions where the same pass through the plate 5, 20 with some soft fabric or fibrous material.

With the above device embodied in the sound chamber and conduits of the talking machine, a greatly improved tone is produced. The exact way in which the tube 25 3 and tension spring 12 in contact therewith act to produce this improved tone is not altogether understood, but that it does improve the same has been thoroughly determined by me in practice. I have, by long 30 and careful experiments, also arrived at the preferred structure herein disclosed of mounting the spring 12 and tube 3 to the outer tube 2.

It may be stated that the tubes 2 and 3 35 are preferably made of wood. I have secured the best results by making the inner tube 3 of birch and the outer tube 2 of sugar pine, although I do not wish to be limited to any specific materials for these 40 tubes. When the parts are once assembled with the tube 3 in concentric relation to the tube 2 and the spring 12 under proper tension, the same will ordinarily not require further adjustment, although the parts may 45 be subsequently adjusted if they have become disarranged. Such disarrangement will be indicated by a decrease in the quality of the tone of the machine.

While I have described the preferred 50 specific materials used in the structure, I wish it understood that any equivalents which may be discovered for these materials are within the scope of the invention and that various changes may also be made 55 in the form, details and arrangement of the parts without departing from the scope of the invention, which, generally stated, consists in the matter shown and described and set forth in the following claims.

60 What is claimed is:

1. The combination with the tone arm of a sound reproducing machine, of concentric spaced tubes located where the sound waves will pass therethrough on their way from 65 said tone arm into the sound chamber of

said machine, and a connection between said tubes, said connection comprising a plurality of layers of yielding compressible material, at least one of the layers of material being of a different degree of compressibility 70 than the other.

2. The combination with the tone arms of a sound reproducing machine, of concentric spaced tubes located where the sound waves will pass therethrough on their way from 75 said tone arm into the sound chamber of said machine, and a connection between said tubes, said connection comprising a plurality of layers of compressible material alternated with thin layers of unyielding material. 80

3. The combination with the tone arm of a sound reproducing machine, of concentric spaced tubes so disposed that the sound waves will pass therethrough on their way from the said tone arm into the sound chamber 85 of said machine, a tension spring in contact with the inner surface of the inner tube, said spring and said inner tube being clamped to the outer tube, and pads interposed between said spring and inner tube 90 and said inner tube and outer tube, said pads being composed of a plurality of layers of compressible material at least one of the layers of material being of a different degree of compressibility than the others. 95

4. The combination with the tone arm of a sound reproducing machine, of concentric spaced tubes so disposed that the sound waves will pass therethrough on their way from the said tone arm into the sound chamber 100 of said machine, a tension spring in contact with the inner surface of the inner tube, said spring and said inner tube being clamped to the outer tube, and pads interposed between said spring and inner tube 105 and said inner tube and outer tube, said pads being composed of a plurality of layers of soft compressible material alternated with layers of incompressible material.

5. The combination with the tone arm of 110 a sound reproducing machine, of concentric spaced tubes so disposed that the sound waves will pass therethrough on their way from the said tone arm into the sound chamber 115 of said machine, a tension spring in contact with the inner surface of the inner tube, said spring and said inner tube being clamped to the outer tube, and pads interposed between said spring and inner tube 120 and said inner tube and outer tube, said pad comprising a central layer of soft fabric and alternately superposed layers of incompressible material and soft compressible material.

6. The combination with the tone arm of 125 a sound reproducing machine, of concentric outer and inner spaced tubes disposed so that their sound waves will pass therethrough on their way from said tone arm into the sound chamber of said machine, and a con- 130

nection between said tubes, said connection comprising a pad having a central layer of soft fabric material and superposed layers at each side thereof of mica and wax impregnated leather.

7. The combination with the tone arm of a sound reproducing machine, of concentric outer and inner spaced tubes so disposed that the sound waves will pass therethrough on their way from said tone arm into the sound chamber of the said machine, a spring element extending substantially parallel to and spaced from the inner surface of the inner tube and having one of its ends bent into contact with said surface, a pad member comprising a plurality of layers of compressible material at least one of the layers of material being of a different degree of compressibility than the others disposed between said spring and the inner tube and between the inner tube and the outer tube, and means for clamping the spring, inner tube and pads to the outer tube.

8. The structure set forth in claim 7, said spring being enveloped at its lower end by a soft compressible material.

9. The combination with the tone arm of a sound reproducing machine, of concentric

outer and inner spaced tubes so disposed that the sound waves will pass therethrough on their way from said tone arm into the sound chamber of said machine, a tension spring spaced from the inner surface of the inner tube and having one of its ends in contact therewith, said spring being clamped at its lower end to said inner tube, and a pad disposed between said lower end of said inner tube comprising a plurality of layers of compressible material at least one of the layers of material being of a different degree of compressibility than the others.

10. The combination with the tone arm of a sound reproducing machine, of concentric outer and inner spaced tubes so disposed that the sound waves will pass therethrough on their way from said tone arm into the sound chamber of said machine, a tension spring spaced from the inner surface of the inner tube and having one of its ends in contact therewith, said spring being clamped at its lower end to said inner tube, said pad comprises a plurality of layers of compressible and non-compressible material alternately disposed.

In testimony whereof I affix my signature. 55
FRED W. COOLEY.
